CALENDAR

Filed Sept. 25, 1928

FIG. 1

FIG. 2

INVENTOR.
ROYAL B. LEE
BY
A. B. Bowman
ATTORNEY

UNITED STATES PATENT OFFICE

ROYAL B. LEE, OF SAN DIEGO, CALIFORNIA

CALENDAR

Application filed September 25, 1928. Serial No. 308,253.

My invention relates to calendars and the objects of my invention are: First, to provide a calendar of this class which may be easily set to indicate the day of any given month and any given year; second, to provide a calendar of this class in which only the month and the year desired is visible at any one time; third, to provide a calendar of this class which is easily set so as to record the desired month and year; fourth, to provide a calendar of this class in which all movable parts are well protected thereby insuring a long life thereof; fifth, to provide a calendar of this class which for any given year necessitates only a slight movement of a disc in order to bring into register any desired month; sixth, to provide a calendar of this class in which extra calculation due to leap year or the lengths of various months is reduced to a minimum; seventh, to provide a calendar of this class which is extremely applicable as an advertising novelty; and eighth, to provide a calendar of this class which is extremely simple of construction proportional to its function, durable, efficient in its action, and which will not readily get out of order.

With these and other objects in view as will appear hereinafter my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a side elevational view of my calendar; Fig. 2 is a transverse sectional view thereof through 2—2 of Fig. 1; Fig. 3 is a fragmentary elevational view of the year and calendar number indicator disc and Fig. 4 is a fragmentary elevational view of the day indicator disc segment which forms the calendar portion of my calendar.

Similar characters of reference refer to similar parts and portions throughout the several views of the drawings.

The calendar casing 1, rotating disc 2 and day indicator disc segment 5, constituting the

principal parts and portions of my calendar.

The case 1 consists of a flat piece of material folded double longitudinally with the extended edges then sealed together forming a thin pocket open at the top and bottom. Rotatably mounted within the case on a rivet 3 extending between the front 1a, and back 1b of the case a little above the center point thereof is a disc 2. A slot 1c having a straight base and an arcuate upper portion is provided in the front side 1a of the calendar casing. The slot 1c exposes the margin of the disc 2 so that it may be rotated by the movement of the operator's finger. A second rivet 4 holds the portion of the case front 1a against the back 1b so as to make the disc 2 readily accessible as shown in Fig. 2.

Arranged in a circular form concentric with the disc 2 are a plurality of numerals 2a which indicate the last two numerals in a given year, such as "28" for "1928." All the numerals of a given year could be placed on this disc if desired. However only half the number of years could be recorded unless the numerals were crowded. Arranged radially between the sets of numerals 2a and the center of the disc are columns of characters 2b which may be letters or numerals, each column containing twelve characters, one for each month of the year. Slots 1d and 1e are provided in the front side 1a of the case. The slot 1d registers with the numerals 2a one set at a time. If desirable the numerals "19" may be printed to the left hand side of the slot 1d so that together with the exposed numerals the full number of the year may be read as shown in Fig. 1 of the drawing.

The other slot 1e is adapted to coincide with and expose the characters 2b one column at a time, and preferably extends in a substantially vertical direction just beneath the slot 1d as shown in Fig. 1.

Listed on the front side of the case 1 are the various months of the year beginning with January and ending with December. The list of months is so arranged that January is opposite the upper character of each column 2b and February is opposite the second character, March the third, and so on until De-

ember is opposite the last or 12th character as shown in Fig. 1.

In order to facilitate the use of the calendar additional printing is provided in connection with the list of months, which may read as follows: During January use calendar number for 31 days. The word "Number" occurs on the one side of the slot 1e and the word "For" on the other side. The corresponding characters on the dial 2 completes the sentence. Similarly the next line reads: "During February use calendar number for 28 days." Because of leap year a special note regarding February is preferably placed just below the list of months. This information consists in stating that every fourth year is leap year followed with a list of years in which February has 29 days instead of 28. Pivotaly mounted preferably on the same pivot 3 which supports the disc 2 is a disc segment 5 which has printed in its lower portion in arcuate substantially horizontal rows numerals 5a reading as follows: 1, 2, 3, 4, 5, 6 and 7, in the first line 2, 3, 4, 5, 6, 7, 8, 9, 10, 11, 12, 13 and 14 for the second line, the numeral 8 being in position under numeral 1, numeral 9 under numeral 2, 10 under number 3 and so on. Similarly the third line reads 9, 10, 11, 12, 13, 14, 15, 16, 17, 18, 19, 20 and 21; the numeral 9 under numeral 2, numeral 10 under numeral 3 and so on.

Line four reads consecutively from 16 to 28 with numeral 16 under numeral 9. Line five reads consecutively from 23 to 31; the numeral 23 under 16 and 31 under 24 of line 4. Line 6 has only the numerals 30 and 31. Each line of numerals is preferably concentric with the pivotal point of the disc segment 5 and each column of numerals extends radially from the point of support thereof. An opening 1f is provided in the lower portion of the front of the case 1a, which uncovers at any one time seven columns of the numerals 5a. Centered just above the opening 1f are letters or abbreviations indicating the various days of the week, beginning with Sunday and ending with Saturday.

A series of characters 5b corresponding to the characters 2b is printed on the disc segment 5. In the structure shown there are numerals which read from left to right as follows: 7, 6, 5, 4, 3, 2, 1. A small hole 1g near the opening 1f uncovers one of these characters 5b at a time. These characters 5b are so arranged that when set to coincide with a given character in one of the columns 2b of the disc 2 the calendar is exposed which corresponds to the month listed opposite that character. Thus, as shown in Fig. 1, the calendar is set so as to read for January, April or July of 1928 as the numeral 1 is in register with the hole 1g.

The disc segment 3 extends slightly below the lower edge of the calendar casing 1 so that it may be shifted to the desired position.

The calendar is operated as follows: First the disc 2 is shifted until the desired year is registered by the slot 1e. The disc segment 3 is then shifted until the hole 1g uncovers a character 5b corresponding with the character 2b opposite the desired month. The calendar may then be read as any other calendar. During a given year only slight movement of the disc segment 5 is necessary in order to bring into register the proper calendar for every month thereof.

It will be noted that there is considerable vacant space upon the face of the calendar where advertising matter or the like may be printed.

Though I have shown and described a particular construction, combination and arrangement of parts and portions I do not wish to be limited to this particular construction, combination and arrangement but desire to include in the scope of my invention, the construction, combination and arrangement substantially as set forth in the appended claims.

Having thus described my invention what I claim as new and desire to secure by Letters Patent is:

1. In a calendar, a case having an opening therein and the days of the week arranged in order adjacent thereto, a segment mounted within said case having numerals thereon corresponding to the possible days in a month, said segment being revoluble so as to bring it to register with said opening, such numerals thereon representing a complete monthly calendar beginning with any given day of the week, reference characters thereon arranged in an arc on said segment, said case having a sight opening adapted to expose any one of said reference characters, and other means mounted in said case having numerals corresponding to years, other reference characters corresponding to said first-mentioned reference characters arranged radially on said other means, each reference character corresponding to a given month for indicating the position of said segment relative to the opening in said case necessary to calendar the days of a given month, said first-mentioned reference characters adapted to identify the correct position of said segment.

2. In a calendar, a case having an opening therein and the days of the week arranged in order adjacent thereto, a segment mounted within said case having numerals thereon corresponding to the possible days in a month, said segment being revoluble so as to bring it to register with said opening, such numerals thereon representing a complete monthly calendar beginning with any given day of the week, reference characters thereon arranged in an arc below said numerals on said segment and correspondingly spaced, said casing having a sight opening

adapted to expose any one of said reference characters, and other means mounted in said case, having numerals corresponding to years, other reference characters corresponding to said first-mentioned reference characters arranged radially on said other means, each reference character corresponding to a given month for indicating the position of said segment relative to the opening in said case necessary to calendar the days of a given month, said first-mentioned reference characters adapted to identify the correct position of said segment, said case having slots therein for exposing a single year date and reference characters corresponding to the months thereof.

In testimony whereof, I have hereunto set my hand at San Diego, California, this 15th day of September, 1928.

ROYAL B. LEE.
